O. R. GREINER

GAS TORCH

Filed Oct. 2, 1922

Inventor
Otto R. Greiner
By his Attorney
Marvin Palind

UNITED STATES PATENT OFFICE.

OTTO R. GREINER, OF PEQUANNOCK, NEW JERSEY.

GAS TORCH.

Application filed October 2, 1922. Serial No. 591,690.

To all whom it may concern:

Be it known that I, Otto R. GREINER, a citizen of the United States, residing at Pequannock, in the county of Morris and State 5 of New Jersey, have invented certain new and useful Improvements in Gas Torches, of which the following is a specification.

This invention relates to improvements in gas torches of the type used in producing a 10 high degree of heat and directing the same as desired in the melting of metals, glass and the like or in cutting metals, as rails, plates and structural shapes.

The principal object of the invention is to 15 provide a blast burner capable of producing a flame of high intensity and melting power.

Another purpose is in the provision of a 20 burner which operates in a relatively quiet manner, substantially freed from the roaring noise of ordinary burners, so injurious to the nerves of an operator, the improved burner producing a smooth flame of intense heat which is readily controlled.

A further aim is to provide a burner 25 torch in which oxygen is admitted in controllable quantity with the fuel gas, air being admitted to produce a softer flame and more steady flow of oxygen and gas.

These and other like objects are attained 30 by the novel construction, combination and arrangement of parts hereinafter described and shown in the accompanying drawing, forming a material part of this disclosure, and in which:—

35 Figure 1 is a partial side, partial sectional view of a torch made in accordance with the invention.

Figure 2 is a fragmentary view of the 40 same looking from another angle.

Figure 3 is a sectional view showing one of the burners in detail.

In the drawing, the numeral 5 designates 45 a pipe connecting with any source of gas supply, the passage in the pipe being controlled by the stop-cock 6 set in its length.

The opposite end 7 of the pipe is preferably contracted and, as shown, may be extended straight out or bent as at 8 at any preferred angle not less than ninety degrees.

50 Entering the pipe 5, near its reduced portion, is the angular bend 9 of a smaller tube 10, the same connecting with a source of

compressed air and having a stop-cock 11 set in its length for limiting the passage of air therethrough.

In a similar manner, a still smaller pipe 12 communicates with the pipe 10 through its angular bend 13 and is controlled by a stop-cock 14 conveniently adjacent to the others, said pipe 12 leading from a stored 55 supply of oxygen.

From the foregoing it will be seen that the gas supplied by the pipe 5 may be mixed with air alone by closing cock 14 and opening cock 11, with oxygen by closing cock 11 60 and opening cock 14, or the gas may be mixed in any desired proportions with both air and oxygen by properly actuating the several controlling cocks.

It has been found that the best results are 65 obtained by arranging the pipe connections as shown, in which the oxygen is first mixed with the air and then the combined air and oxygen with the gas.

At the end of the pipe 8, whether straight 70 or curved, is a regulating stop-cock 15 and leading from it is another pipe 16 also contracted or diminished in area, as at 17, the continuing portion 18 being bent at an angle 19 and its end screw-threaded exteriorly 75 to suit the bases of interchangeable burner tips 20.

Said tips are made with different sizes of 80 apertures 21 to suit varying work conditions, their bases 22 being uniform as shown 85 and sets of five are preferably supplied with each burner, thus permitting a wide range of operation.

It is necessary in constructing the torch to 90 avoid sharp corners, bends so far as possible and to provide round holes through the plugs of the cocks, such holes having substantially the same cross sectional area as that of the pipes in which they are placed.

In operation the cock 15 is opened, then 95 gas cock 6, the issuing gas being ignited at the burner tip.

Then the air cock 11 is slightly opened after which the oxygen cock 14 is opened until the flame at the tip is blue. Excess of 100 oxygen should be avoided as unnecessary in obtaining even a high temperature.

Having thus described my invention and set forth the manner of its construction and

application, what I claim as new and desire to secure by Letters Patent, is:—

A gas torch for heating comprising a gas pipe, an air pipe entering said gas pipe, an oxygen pipe entering said air pipe, independent cocks on each of said pipes, a reduced extension on said gas pipe, a regulat-

ing cock on said extension, and means for engaging a burner tip on the end of said extension.

In witness whereof I have affixed my signature.

10

OTTO R. GREINER.
